LEVI S. DEMING, OF NEWINGTON, CONNECTICUT.

Letters Patent No. 91,723, dated June 22, 1869.

IMPROVEMENT IN GATES.

The Schedule referred to in these Letters Patent and making part of the same.

To all whom it may concern:

Be it known that I, LEVI S. DEMING, of Newington, county of Hartford, and State of Connecticut, have invented certain new and useful Improvements in Gates; and to enable others skilled in the art to make and use the same, I will proceed to describe, referring to the drawings, in which the same letters indicate like parts in each of the figures.

The nature of this invention consists of a perpendicular shaft, arranged underneath the gateway, the lower end of which takes its bearing and vibrates in a fixed step, while the upper end is steadied in one direction by a vibratory arm, and is supported in the other direction by the gate-connections, so that as the approaching carriage-wheel strikes the brake in the common way, its connection causes the shaft to turn, first in one direction, then in the other, this shaft also being provided with a projecting weight, so that as it (the weight) passes the perpendicular line, it throws the upper end of the shaft into an incline position, and imparts force, and accelerates the action of the gates, to open or close by means of the common connection.

It further consists of an arm or notched wheel, secured upon said shaft, and acts upon an eccentric-weighted lever, which with its connection depresses the fastening which holds the gates closed, and allows the gates to freely open.

In the accompanying drawings—

Figure 1 is an elevation of the actuating-mechanism of this invention.

Figure 2 is a top view of the connections secured to the lower end of the gates, and to the upper end of the shaft.

Figure 3 is a view of the gates, showing the fastening by which they are held in a closed position.

Figure 4, sheet 2, is a side elevation of the actuating-mechanism.

Figures 5, 6, 7, and 8, are views of detached portions thereof.

a is a shaft, the lower end of which takes bearing in a fixed step, *b*, underneath the gateway. The upper end of this shaft is held in nearly a perpendicular position, in line from one side of the gateway to the other, by an arm, *c*, one end of which is secured to the upper end of the shaft *a*, and the other end to the frame-work or stud under the drive-way. Thus, this shaft is held nearly in a perpendicular position, cross-wise of the drive-way.

d is a connection-plate, or arm, secured to the upper end of the shaft *a*, the ends of which are, or may be bent or formed at right angles therewith, and perforated to receive a screw-threaded connection, *e*, so that its length, or position of the shaft *a* may be adjusted by means of nuts *f* or hooks, &c.

g is a swivel-connection, for uniting the opposite portion of the chain or rod-connections, and for the purpose of taking up or letting out one side or the other, as desirable, to nicely adjust the action of the mechanism.

The chain-portion *h* of these connections passes around the lower end of the gate-shaft *i*, and is secured thereto by a screw, or staple, *k*, which completes the connection of the upper end of the shaft *a* with the shafts *i* of the gates.

j is a weight, secured to a projecting arm of the shaft *a*.

This weight may be cast on to one side of the shaft, or made adjustable on the arm, by means of a key-screw, or other suitable means. The object of this weight is to give force, and accelerate the action of the gates, as it (the shaft *a*) rotates and passes a perpendicular line, into an incline position in either direction, in opening or closing the gates.

The rotating action of this shaft *a* throws the weight *j*, first from an incline position, one side of a perpendicular line, into an opposite incline position, the other side of a perpendicular line, the tendency of which is to hold the gates either open or closed, until again operated upon by the brake in the common way.

The rotary action of this shaft *a* is produced from the brakes in common use, by connections passing around said shaft, and secured thereto substantially as shown at A, fig. 2.

Near the lower end of this shaft *a* is secured an arm, or notched wheel, *l*, and so arranged thereon, that when the shaft commences to rotate, the arm or notch *m* will lift the weight or outer end *n* of the eccentric lever *o*, which, by its connections *o'*, depresses the gate-fastener *p*, and allows the gates to freely open, by the continued action of the shaft and weight *a* *j*. And when the brakes again act upon the shaft to close the gates, the lever *o*, by means of the weight *n*, will lift the fastener, so that the gates, as they close, will ride over said fastener, and be firmly held in a closed position, until again acted upon as before.

The same principle of a weighted lever, I purpose to attach to the gate, so that the fastener may be actuated or depressed, by a foot or hand, to open the gate.

The other portions of the mechanism for operating or completing the gate are like those in common use. I will not further describe.

I believe I have thus shown the nature, construction, and advantage of this invention, so as to enable others skilled in the art to make and use the same therefrom.

What, I claim, therefore, and desire to secure by Letters Patent, is—

1. In a self-acting gate, the vibratory shaft *a*, swinging weight *j*, arranged and operating substantially as and for the purpose described.

2. The arm or notch-wheel *l*, eccentric lever *o*, connection *o'*, gate-fastening *p*, arranged and operating substantially as and for the purpose described.
